ENVELOPE OPENING MACHINE

Edward J. Dummer and Azel Gay, Rochester,
N. Y., assignors to Multipost Co., Rochester,
N. Y., a corporation of New York

Application December 24, 1936, Serial No. 117,486

2 Claims. (Cl. 164—61)

Our present invention relates to paper feeding and cutting machines and more particularly to envelope or mail opening machines of the type in which the letters either piled or singly may be run rapidly through and one of their marginal edges neatly slit to just remove the fold without injuring the contents, and it has for its object to provide a simple, efficient and improved machine of this character that may be conveniently operated at high speed and capacity and yet with surety of accurate performance. The improvements are directed particularly toward the provision of a particular presser means for holding the letter or envelope against its conveying belt and its guiding means at the cutting point that will adapt itself to letters having unusual thickness and bulk. To these and other ends, the invention resides in certain improvements and combinations of parts, all as will be hereinafter more fully described, the novel features being pointed out in the claims at the end of this specification.

In the drawings:

Fig. 1 is a front elevation of a letter opening machine constructed in accordance with and illustrating one embodiment of our invention;

Fig. 2 is a top plan view thereof;

Fig. 3 is a vertical section taken substantially on the line 3—3 of Fig. 1 and viewed in the direction of the arrows;

Fig. 4 is a top plan view similar to Fig. 2 but with the bed plate and casing shell removed to disclose interior parts, particularly in the mounting of the feed belt;

Fig. 5 is a detail view from the front partly broken away of the adjusting screw connection for moving the bed plate;

Fig. 6 is a detail sectional view through said adjusting screw;

Fig. 7 is an enlarged front view of the knives and the edge guide, the intervening parts removed;

Fig. 8 is an enlarged detail sectional end view of the presser feet as they appear in Fig. 3 but with intervening parts omitted, and

Fig. 9 is a similar enlarged view of the gate in rear of the presser feet which allows the envelopes to climb the belt only one at a time, and

Fig. 10 is a view similar to Fig. 8 illustrative of the action of the presser feet on a passing envelope.

Similar reference numerals throughout the several views indicate the same parts.

Referring more particularly to the drawings, 1 and 7 with the driven knife 20. The stud 29 is hollow and contains a spring 33 that reacts against a plate 34 secured to the end of the bearing box by two screws 35. The knife 32 is thus

urged forwardly continuously by the spring against the driven knife 20 to itself be frictionally driven by the latter.

As best shown in detail in Fig. 7, an extension 36 on the end of the back plate or guide 6 of the bed plate 5 projects toward the knives and has a tapered end 37 that enters between them at their intersection running as closely as possible to the bite or cutting point of the blades.

10 This extension is V-shaped in cross section, as shown also in the other figures, but the bottom at the inside apex is definitely flat, as indicated at 38, lies in the plane of the guide wall 6 and this plane is sufficiently back of the cutting plane

15 defined by the contacting surfaces of the knives to cut off the fold of the envelope edge back the desired distance. The mode of regulating the width of this cut will be later explained. The lower plate 39 of the edge guide inclines down-

20 wardly outwardly to contact with the bed plate 5 while its longitudinal projection toward the feed end of the machine is given a compound curve into which the lateral inclination merges, whereby it also inclines downwardly at the receiving

25 end to meet the surface of the bed plate and form a ramp portion 40 up which the envelopes slide to enter the edge guide against the wall 38. The upper plate of the V at the corresponding end has a share portion 41 where it joins the plate

30 6 for a similar purpose.

This V-guide is more particularly described and claimed in our copending application, Ser. No. 234,833; filed October 13, 1938, which is a division hereof.

35 As so far described, in operation the undermost letter of a pile squared against the back wall 6 and the gate 7 touches or is urged by the operator against the belt 25. It is carried under the gate and the frictional hold of the belt thereon causes it to overcome the retarding influence of a spring

40 finger 42 on the far side of the gate having a notch 43 therein (Fig. 9) to accommodate the belt. The finger has a rounded lower edge which, however, arrests the envelope next above until the first one, whose frictional contact might

45 otherwise carry it with it, has passed on. This adjacent one in turn contacts the superior friction of the feed belt and is next fed forward. The latter carries each envelope along the edge guide through the knives which slit the fold thereof and then passes out at the right end of the machine in opened condition.

The said retarding finger 42 is mounted on a shaft 44 extending between the securing flange and a front flange 45 of the gate plate 7 and is pressed downwardly by a spring 46 coiled about such shaft. A lug 47 on the finger carries a stop screw 48 that bears against a lug 49 on the gate to limit the downward thrust of the finger with reference to the belt and to the nature of the mail matter that is passing through.

It is, of course, important that as the envelope enters the knives its edge should be firmly and evenly pressed against the wall 38 of the edge guide so that the fold thereof will be uniformly and evenly sheared off to exactly the desired extent. This is insured by the following provisions: In the first place, the direction of travel of the upper reach 26 of the belt is not strictly longitudinally of the bed but converges inwardly

70 from pulley 23 to pulley 22. In addition to this, the axis of pulley 23 is cocked in two planes intersecting the plane of the axis of pulley 22, as clearly appears in Fig. 4, that is, the stud is tilted downwardly and also laterally bringing the pul-

leys out of line on two angles. The result is that the reach 26 of the belt twists or rotates on its own geometrical axis toward the knives as it passes from the one pulley to the other in the feeding direction, as indicated by the arrows in Fig. 4. Its frictional effect on the envelope is, therefore, both to convey it in a straight path and to urge it laterally toward the knives and against the edge guides 36.

This conveying means is more particularly described and claimed in our copending application, Ser. No. 186,357, filed January 22, 1938, which is a division hereof.

At the cutting point, the envelope is held to the knives in one construction by compressor feet 50 and 51, best shown in Figs. 1, 3, 8 and 10. These are jointly notched at 52 to span the feed belt and are pivoted upon a stud 53 projecting from the vertical frame piece 2. The inner foot 50 is provided with a lug 54 engaging beneath the 11 foot 51. The latter is pressed downwardly by a spring 55 coiled about the stud so that through the lug it also presses down companion foot 50. The latter, however, is provided with a stop screw 56 engaging a lug 57 on the frame to regulate the 12 maximum depression of both feet with respect to the belt and the envelope carried thereon. Also, it will be obvious that, while foot 51 may rise independently, the lifting of inner foot 50 raises outer foot 51 with it if the latter is not already 13 above contact with the lug. The purpose of this is best illustrated in Fig. 10. Inner foot 50 rides on the thin edge portion of the envelope A into which its contents B do not project and cooperates with the guide to present the edge fold squarely 14 to the knives. Foot 51 rides on the bulged body of the envelope exerting enough retarding effect to keep it from slewing around when the resistance of the knives is met and with an extremely bulky envelope rises independently, as described. 15 The under side of the contact portion of foot 50 is preferably inclined downwardly toward the cutting plane.

To regulate the width of the strip cut from the envelope edge, the following arrangement is provided: Bearing in mind that the vertical cutting plane of the knives is fixed and that the back guide wall 6 and the edge guide 36 are both carried by and fixed with relation to the bed plate 5, the latter is capable of pivoting on the screw 19 at its extreme left or feed end whereby its opposite end may swing toward and from the knives on that center, thus carrying the edge guide 36 closer to or farther in rear from the cutting plane. The bed plate 5 is provided outside the casing 1 with depending slightly spaced flanges 60 and 61. The front flange 60 is notched to take in the groove between collars 62 on a thumb screw 63 threaded into the end frame piece 1^a at 64. This tapped hole 64 is counterbored at 65 so that the inner collar may enter and carry the flange close against the frame when the screw is screwed all the way in. By this means the bed is swung forcibly in or out with a fine adjustment depending upon the fineness of the thread. Extending through a slot (not shown) in the end flange 61 of the bed plate at its swinging end is a clamping nut 66 that is threaded into the end wall 1^a of the frame to clamp the bed in its adjusted position. We recommend that both of these adjusting and clamping thumb screws be made small and fitted very snug so that a correct adjustment once set by an authorized operator will not be disturbed by idlers thoughtlessly turning the heads.

We claim as our invention:

1. In an envelope opening machine, the combination with a bed plate, a knife arranged angularly thereto, means for feeding envelopes along the bed and an edge guide for the envelopes associated with the knife to direct the edge of an envelope in the cutting plane thereof, of a yielding presser foot adapted to engage the edge portion of the envelope at the cutting point and a companion presser foot adapted to yieldingly engage the body of the envelope.
2. In an envelope opening machine, the combination with a bed plate, a knife arranged angularly thereto, means for feeding envelopes along the bed and an edge guide for the envelopes associated with the knife to direct the edge of an envelope in the cutting plane thereof, of a yielding presser foot adapted to engage the edge portion of the envelope at the cutting point and a companion presser foot adapted to yieldingly engage the body of the envelope.

larly thereto, means for feeding envelopes along the bed and an edge guide for the envelopes associated with the knife to direct the edge of an envelope in the cutting plane thereof, of a yielding presser foot adapted to engage the edge portion of the envelope at the cutting point, and a companion presser foot adapted to yieldingly engage the body of the envelope, the last mentioned foot being adapted to yield independently of the first but having a connection therewith through which it may also be raised thereby. 5

EDWARD J. DUMMER.
AZEL GAY.
